UNITED STATES PATENT OFFICE

PHILIP SUBKOW, OF LOS ANGELES, CALIFORNIA, ASSIGNOR TO UNION OIL COMPANY OF CALIFORNIA, OF LOS ANGELES, CALIFORNIA, A CORPORATION OF CALIFORNIA

AUTOMATIC FLUID-PRESSURE PUMP

Application filed January 9, 1929. Serial No. 331,267.

This invention relates to automatically operating devices for pumping liquid with fluids under pressure, and is especially adapted to the pumping of oil wells by the so-called 5 gas lift method wherein gas under pressure is employed as the pressure fluid.

One method of using gas under pressure to pump a liquid from a deep well employs an automatically operating valve mechanism 10 actuatable in an upward direction by rock pressure to cut off gas flow and permit liquid to enter a discharge chamber and actuatable downward by gravity to admit gas under pressure into and under a column of liquid received 15 in said chamber and simultaneously to cut off liquid entrance. During the period when the gas is being admitted to displace the oil in the flow tube, the gas-oil ratio increases as the oil is being discharged, since the pressure 20 of the gas at the casing head is usually not altered. In devices of this type as actually employed there is a lag in the operation of the valve to cut off the gas flow, this lag being due to a back pressure in the lower end 25 of the flow tube after the oil column has been expelled and caused by the friction in the flow tube due to the gas stream which prevents pressure drop to permit valve actuation. This back pressure simulates the action of a 30 head of oil and tends to keep the oil inlet valve closed causing the gas admission valve to remain open for a longer period than is required by the actual head of oil. This results in a considerable loss of gas.

In this invention there is a provision of 35 means to shut off the gas when a certain gas velocity, i. e. a certain difference in the gas pressure and the back pressure in the oil discharge tube, is reached, and this means, being 40 so adapted as to shut off the gas at the time when the efficiency of the lift due to the discharge of the oil is reduced to low amount, will act to save gas and increase the efficiency of the device. The means for shutting off the 45 gas when it reaches a certain velocity, i. e. a certain minimum back pressure in the lift tube, also prevents the gas admission valve from remaining open too long, since when the gas velocity reaches a predetermined 50 limit, the gas is shut off, permitting the pres-

sure to dissipate and thus allowing the oil admission valve to open.

I have discovered that by installing in the flowing device, an automatically actuating mechanism such as a spring controlled dart valve, the gas flow can be cut off whenever the rate of such flow reaches a predetermined maximum. The gas flow thus having been suddenly interrupted the oil control valve will open by reason of the rock pressure thereby closing the valve mechanism which normally controls the gas flow. Upon cessation of said gas flow the dart valve is immediately moved to its opposite position by a spring. This valve may be employed also to prevent entrance of oil to the gas passages and to the gas control valve mechanism. Thus quick operations are assured and gas losses are prevented.

The invention therefore may be said to reside in mechanisms automatically actuated when gas flow exceeds a predetermined rate, in combination with an oil control valve connected with and operating to open and close valve mechanisms controlling the passage of gas under pressure; the oil control valve according to a preferred form opening under influence of well pressure and closing by gravity when a certain balance between this pressure and the pressure in the tube is reached. Or more broadly stated the invention comprises a velocity actuated valve mechanism cooperating with pressure- and gravity-operated gas and oil control valves to permit said valves to function when the gas velocity exceeds a predetermined value.

In the accompanying drawings wherein one embodiment of the invention is shown as a means of illustration,

Fig. 1 is a vertical section through a gas pressure pump actuated by valve mechanism, according to the present invention, the oil control valve being shown as closed and the gas control valve mechanism being shown as open;

Fig. 2 is a vertical section through the fluid pressure pump but showing the oil control valve open and the gas control mechanism closed;

Figs. 3 and 4 are respectively cross sections

100

taken on the lines 3—3 and 4—4 of Figs. 1 and 2; and

Fig. 5 is chiefly an elevational detail, certain parts however being broken away to show how the pump is placed in a column and indicate certain stages of operation.

In these drawings the usual casing 10 is provided with a casing head 11 for the introduction of gas under pressure by way of an inlet 12, a discharge pipe or flow tube 13 depending within the casing and carrying upon its lower end a fluid pressure pump 14 whose lower extremity is in the form of a fitting 15 secured in a packer 16 which confines the oil body below the packer 16 so as to permit it to enter the pump only and to exclude it from the gas chamber thus formed between the casing 10 and the pump and flow tube.

In addition to the fitting 15 the body of the pump 14 carries at its upper end a second fitting 18 connected with the flow tube 13 and provided with an integral spider 19 which leads from opposite sides of the fitting 18 to form gas passages and converges centrally into a nipple 20 upon which is mounted a valve housing 21 provided with oppositely extending arms in each of which there is positioned a rotary gas admission valve 22.

Each valve 22 is actuated through the medium of externally disposed arms 23 slotted to receive connecting pins 24 carried in the arms of a yoke 25 formed upon the upper end of a stem 26 of an oil admission valve 28 adapted to rest upon a valve seat 29 carried upon and closing the lower end of the pump housing 14. The proper positioning of the seat 29 with respect to the valve stem 26 and the valves 22 is insured by a bracket 30 extending between said seat and the valve housing 21 and conveniently carrying a guide 31 for said valve stem.

The outer ends of the arms of the valve housing 21 are provided with housings 32 for dart valves 33 normally actuated downward by springs 34 to prevent entrance of liquid into the gas ducts 35 which are fed from the interior of the housing 21 by the gas supplied through the passages in the spider 19. When the dart valves 33 are moved to upper position against the tension springs 34, they serve to close the outlets 36 through which the gas is introduced into the chamber 38 within pump housing 14 and around spider 19 and valve housing 21.

The space between the casing 10 and the flow tube 13 serves to conduct gas under pressure to the gas inlet passages in the spider 19 of the fitting 18. The chamber 38 within said pump housing 14 and around the valve mechanisms carried thereby, cooperates with the interior of the flow tube 13 to receive a body of oil forced past the valve 28 as indicated in Fig. 2, by the natural pressure of the oil entering the well beneath the packer 16.

In operation, the space between casing 10 and tube 13 is filled with gas under suitable pressure, and at the commencement of a cycle the oil control valve 28 will be moved to elevated position as indicated in Fig. 2 by the flow of oil upward against the valve 28 under influence of the natural pressure of the well. When the valve 28 is in such elevated position stem 26 serves through the medium of the arms 23 to hold the valves 22 in closed position and thereby prevent passage of gas from the spider 19 through the ducts 35 into the chamber 38, and the dart valves 33 will engage their lower seats to prevent the entrance of liquid into said ducts 35. This condition will be maintained until the flow of oil past the valve 28 ceases or falls to such a low value that gravity will cause the valve 28, which has considerable mass, to drop into its seat 29. This will occur when any existing gas pressure plus the hydrostatic head of the oil column balances the formation pressure. As the valve 28 descends it operates arms 23 to rotate the valves 22 and permit flow of gas through the ducts 35, the pressure of such gas being sufficient to overcome the tension of the springs 34 to lift the dart valves 33 from their lower seats and maintain them in an intermediate position as indicated in Fig. 1, the gas therefore normally flowing past said dart valves 33 and through the ports 36 into the chamber 38. The gas issues under the oil column in the tube 13 and the flow of gas continues for a time sufficient to elevate the oil column and discharge the greater portion thereof at the surface.

As the oil column is discharged and its weight therefore gradually reduced, the velocity of the gas increases accordingly, thereby tending to increase the gas-oil ratio. At the same time a material gas pressure is being maintained in the pump 14 downward on the face of the valve 28 due to frictional resistance in the tube 13 as well as to the residual oil load therein. The reduction in load, as the end of the discharging operation is approached, does not result promptly in a sufficient pressure drop to insure the opening of the valve 28 by the natural pressure of the oil in the well. However, the pressure drop (due to oil discharge) is such that the velocity of the gas past the dart valves 33 (i. e. the difference in pressure on the two sides of the dart valves) soon reaches a rate so high that the tension of the springs 34 is entirely overcome. The ports 36 are therefore closed by valves 33 as soon as the passage of gas becomes excessive and therefore wasteful, such closing of valves 33 occurring at a time when the back pressure in the pump member 14 is still material. The resultant stoppage of gas flow permits the pressure of the gas in the tube 13 to exhaust quickly and thereby reduce the back

pressure upon the upper face of the valve 28, so that valve 28 is opened by the oil pressure and the valves 22 are closed through arms 23 as seen in Fig. 2. The oil rises again in the tube 13 until the head developed thereby balances rock pressure and the pumping cycle is repeated. In order that the gas trapped under high pressure in ducts 35 may vent to permit the return of the dart valves 33 by their springs 34 to their lowermost positions as in Fig. 2, any relatively insignificant leakage may be relied upon, such as a normal leakage around the upper valve seats, or through a groove in such valve seats, or other small vent which will insure movement of said dart valves to said lowermost positions during the time intervals required for filling the flow tube with oil.

From the foregoing will be clear that the employment of an automatically actuated device such as a dart valve 33 under the tension of a spring 34 properly selected for the pumping conditions to be met, will result in timely operation of the oil admission valve 28 to close the gas admission valves 22 with a consequent prevention of the passage and loss of excessive quantities of gas.

While I have disclosed a preferred embodiment of the invention, it is to be understood that such embodiment is merely illustrative of the generic invention and that the invention is limited only as defined in the following claims.

I claim:

35. 1. A fluid pressure device for flowing liquids comprising a housing enclosing a receiving chamber, a liquid control valve actuatable in one direction by liquid pressure outside the chamber and in another direction by gravity, a gas admission valve actuatable thereby, and an additional valve actuatable to one position by a velocity of gas to cut off gas admission when the velocity reaches a predetermined maximum.
40. 2. A structure according to claim 1 wherein the velocity actuated valve is spring operated toward the opposite direction to close a gas passage against liquid entrance in the absence of gas flow.
45. 3. A construction according to claim 1 wherein the velocity actuated valve is a double-acting dart valve, a seat being provided for the valve to cut off gas flow, and a second seat being provided for the other end of the valve to prevent liquid return when no gas flows.
50. 4. A construction according to claim 1 wherein the upper end of the housing is permanently open.
55. 5. A fluid pressure device for flowing oil wells and the like comprising a pump housing defining a receiving chamber and permanently open at its upper end for connection with a flow tube, an oil admission valve at the lower end of said housing actuatable upward

by pressure of the oil within the well, and downward by gravity, a gas admission valve connected with said oil admission valve and actuatable thereby to cut off gas flow during oil admission, and an additional valve actuatable by velocity of the gas to cut off gas flow when the velocity reaches a predetermined maximum.

6. A construction according to claim 5 wherein the gas admission valve is a rotary valve.

7. Means for flowing oil wells and the like comprising a casing depending into a well, a flow tube depending into the casing, a pump housing carried on the lower end of the flow tube, packing means positioned between the casing and the lower end of the pump housing whereby a gas supply passage is provided above the packer between the casing and the flow tube, said housing defining a receiving chamber in permanent communication with the interior of said flow tube, said housing having a gas conduit leading from the exterior thereof into said chamber, an oil admission valve at the lower end of said housing actuatable upward by pressure of the oil within the well and actuatable downward by gravity, a gas admission valve connected with said oil admission valve and actuatable thereby to cut off gas flow during oil admission, and an additional gas control valve positioned beyond said gas admission valve and actuatable by velocity of flowing gas to cut off gas flow when the velocity thereof reaches a predetermined maximum.

CERTIFICATE OF CORRECTION.

Patent No. 1,740,793.

Granted December 24, 1929, to

PHILIP SUBKOW.

It is hereby certified that error appears in the printed specification of the above numbered patent requiring correction as follows: Page 1, line 28, before the word "pressure" insert the words "a prompt"; and that the said Letters Patent should be read with this correction therein that the same may conform to the record of the case in the Patent Office.

Signed and sealed this 25th day of February, A. D. 1930.

M. J. Moore,
Acting Commissioner of Patents.
